(57) CLAIM

The ornamental design for a beverage carafe, as shown and described.

DESCRIPTION

FIG. 1 is a top, front, left perspective view of a beverage carafe showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, rear, right perspective view thereof.

1 Claim, 8 Drawing Sheets
